EDWARD C. STODDARD, OF PLYMOUTH, CONNECTICUT.

DESIGN FOR A CLOCK-CASE.

Design No. 19,267, dated August 13, 1889.

UNITED STATES PATENT OFFICE.

EDWARD C. STODDARD, OF PLYMOUTH, CONNECTICUT.

DESIGN FOR A CLOCK-CASE.

SPECIFICATION forming part of Design No. 19,267, dated August 13, 1889.

Application filed July 18, 1889. Serial No. 317,947. Term of patent 7 years.

To all whom it may concern:

- Be it known that I, EDWARD C. STODDARD, a citizen of the United States, residing at Plymouth, in the county of Litchfield and State of Connecticut, have invented and produced a new and original Design for a Clock-Case, of which the following is a specification, reference being had to the accompanying photograph, forming part thereof.
- 10 My design for a clock-case consists in a cross having a step-like base, with the clock-dial on the face of said base. This constitutes the leading feature of the design. The incidental features are certain ornamental figures upon the face of the cross and its base.
- 15 A designates the cross, the upright portion of which is ornamented on its face by scroll-like figures *b*, and the horizontal portion of which is ornamented on its face by letters of the alphabet which simulate an inscription.
- 20 B designates the base, which has a step-like

configuration, ornamented on its face by figures *c c*, simulating numerals, star-like ornaments *d d*, triangular-shaped ornaments *e e*, with figures simulating the letters "I. H. S." 25 between them, a central flower-like ornament *f* on its lower portion, flanked by reversely-inclining block-like ornaments *g*, and a panel-like figure *h* on its upper portion, on which appears the dial *B* of the clock, *i i* designating the clock-hands.

I claim—

The design for a clock-case herein shown and described, the same consisting in the representation of a cross having a base of step-like configuration, with the clock-dial on the face of said base. 35

EDWARD C. STODDARD.
